(57) **CLAIM**

The ornamental design for the hair clipper, as shown and described.

DESCRIPTION

FIG. 1 is a first perspective view of the hair clipper in accordance with the principles of the present disclosure;

FIG. 2 is a second perspective view of the hair clipper;

FIG. 3 is a left side elevation view of the hair clipper;

FIG. 4 is a right side elevation view of the hair clipper;

FIG. 5 is a top plan view of the hair clipper;

FIG. 6 is a bottom plan view of the hair clipper;

FIG. 7 is a front elevation view of the hair clipper; and,

FIG. 8 is a rear elevation view of the hair clipper.

The broken lines shown in the drawings illustrate portions of the article and form no part of the claimed design.
